PETER FUNK AND JO. NICODEMUS BAADER, OF BUFFALO, NEW YORK.

Letters Patent No. 103,037, dated May 17, 1870.

IMPROVED INSECT-TRAP.

The Schedule referred to in these Letters Patent and making part of the same

We, PETER FUNK and JO. NICODEMUS BAADER, both of the city of Buffalo, county of Erie and State of New York, have made certain Improvements in "Insect-Traps," of which the following is a specification.

The nature of our invention consists in constructing a machine or trap for the killing of insects, so arranged that, when the trap-board B is set, the same will have to be disengaged from the snap-bolt or trigger H, by the attendance of a person, in order to catch and kill the insects that may be within reach of the trap-board B. The trap-board B, when disengaged from the trigger H, to sweep over the case or bait-plate A, in order to drive the insects into the killing-pit or case, where the same are crushed by the blow of the trap-board B. We refer to the drawing and letters of reference marked thereon making part of this specification, and which shows our invention more fully.

Letter A, in the drawing, represents the base-board. The same is provided with a number of small troughs for the purpose of receiving the bait, and is of segmental shape.

To the base-board A is secured a killing-pit or case, marked D. Said killing-pit is provided with a hinged bottom, E, and also with a trap-board, B, which is also hinged to the same, and with two blade-springs F, which are acting upon trap-board B, as plainly seen in the drawing.

A post, G, is secured to the bait-plate, and is provided with a snap-bolt, H. Said bolt is surrounded by a coiled spring which acts upon bolt H. To the bolt is secured a string for the purpose of disengaging the trap-board B from the bolt by pulling on said string.

The trap-board B is provided on the end with a catch blade-spring, I, which engages with the bolt H, as plainly illustrated.

It will be observed that the trap-board B, in the position as represented in the drawing, is set, and may, at any time, by pulling on the string secured to bolt H, be made to deal the blow upon the bottom-board E, when the same is in its proper position; that is, when the same is brought in a position so as to come flush with pit or apartment D. When the bottom board E is in the position as represented in the drawing, the insects which were killed by the blow of the trap-board B may be removed from the bottom-board E.

It will also be observed that, in order to set the trap, the board E has to be brought in its proper position, and the trap-board B has to be engaged with the snap-bolt H.

Claim.

Having thus fully described our invention, What we claim as new, and desire to secure by Letters Patent, is—

The construction and arrangement of the base-board A with corrugators, in combination with the trap-board B, the killing department D, the trap-board E, the catch I, and bolt H, all to operate as described, and for the uses set forth.

PETER FUNK.
JO. NICODEMUS BAADER.
